UNITED STATES PATENT OFFICE.

FRANZ LÖSEL, OF BRUNN, CZECHOSLOVAKIA.

ELASTIC-FLUID TURBINE.

Application filed August 4, 1923. Serial No. 655,722.

To all whom it may concern:

Be it known that I, FRANZ LÖSEL, a citizen of the Republic of Czechoslovakia, and residing at Brunn, Czechoslovakia, have invented certain new and useful Improvements in and Relating to Elastic-Fluid Turbines, of which the following is a specification.

In the known types of steam or gas turbines having an axially divided casing the pressure of the driving fluid performing work in the turbine has the tendency to force the axial connecting flanges apart and to cause them to form clearances and to become leaky, necessitating the use of heavy casings and connecting flanges for withstanding these internal pressures. Such casing structures increase the danger and reduce the reliability particularly by utilizing elastic working fluid of high pressure and of high temperature or high superheat due to the heat expansions and stresses thereto and also due to their inequality. The object of the present invention is to neutralize this effect of the internal pressure and to utilize the internal pressure within the casing for rendering automatically all the axial joints particularly the axial casing joints and the divided parts thereof tight and to obviate these objections. This is effected according to the present invention by the provision of a separate reinforcing casing for the high pressure side surrounding the axially divided rotor enclosing casing on its higher pressure end and correlated therewith in such manner as to cause the driving fluid to exert an equalizing pressure upon the axially divided rotor enclosing casing inwardly toward the axis, and it is advantageous to have a pressure at least approximately equal to but preferably greater than the internal pressure thereof to assist in maintaining the axial joints tightly closed. The reinforcing part forming the high pressure admission or front end of the turbine casing is made preferably of pressed or rolled material, (wrought iron, boiler plate) of great tensile strength, is axially undivided and surrounds and firmly engages the higher pressure end of the axially divided part of the casing preferably made of cast material extending

into it. The reinforcing higher pressure casing, therefore, functions to reinforce the inner casing for lower pressure while the counter or opposing pressure of the driving fluid exerted thereupon neutralizes or tends to neutralize the internal pressure of the inner casing, and presses or tends to press its axial joints tightly together and keeps them tight. Advantageous features of the invention are simplification of the axial joint connections, improvement of the high pressure turbine constructions, improvement in reliability and security or safety, self-tightening joints etc.

The accompanying drawing shows several constructional examples of the invention,

Fig. 1 being a longitudinal section through a high pressure steam turbine constructed according to the invention,

Fig. 2 a cross-section along line A—B of Fig. 1 and

Figs. 3 and 4, 5 and 6, 7 and 8, 9 and 10 being other constructional forms.

a is the turbine rotor, *b* the part of the casing under greater pressure and *c* the part under lower pressure. The high pressure part *b* is not divided axially, while the low pressure part *c* is axially divided and held together by means of the flanges *i* and the bolts *k* (Fig. 2). The two parts *b* and *c* of the casing are connected together in abutting relation in a radial plane by annular flanges *p*, *q* and bolts *r*, the latter resisting pressures tending to separate the casings axially. The casing *b* is also connected with and firmly engages externally an annular shoulder *c'* formed below the radial abutting surface of the flange *q* and thereby opposes separation of the divided parts *c*.

The cylinder *t* supporting the diaphragms *n* is also axially divided and is firmly connected to the low pressure part *c* of the casing preferably by being cast in one piece with it, as shown in Fig. 1. The cylinder *t* is surrounded on all sides by the driving fluid and is capable of following the expansions due to heat without hindrance.

The undivided high pressure part *b* of the casing takes up the outwardly acting pressure of the driving fluid. In the embodiment herein shown the pressure between the casings *b* and *t* is greater than the inter-

nal pressure of t and hence the driving fluid exerts a greater pressure on the axially divided supporting part t for the guide nozzles in the direction towards the axis than in the opposite direction, and, since the part t is fixed to the part c of the casing, keeps all the axially directed joints closed, while the connection of the undivided high pressure part b to the low pressure part c assists in keeping the joints of the latter closed.

The high pressure part b of the casing is preferably made of rolled or pressed material of great tensile strength, for instance of boiler plate, and the tensile strength of the wrought iron part b of the casing may be utilized for holding the axially divided parts closely together. For this purpose, as is seen in Figs. 3 and 4, a cylinder e with stiffening ribs f is cast in one piece with the low pressure part c and the cylinder t . This cylinder e is held together by the part b of the casing, which is slid over it. The outer surface of the cylinder e is preferably provided with shallow recesses g , into which the driving fluid can enter.

Instead of the cylinder e (Figs. 3 and 4) other abutment surfaces can be provided on the cylinder t , for instance axial fitting surfaces h (Figs. 5 and 6) or annular ribs j (Figs. 7 and 8), which are firmly surrounded by the part b of the casing. The annular ribs j are provided with holes l , through which the driving fluid can circulate. Figs. 9 and 10 show another alternative arrangement with bracing members disposed within the elastic fluid chamber between the casings b and t . The left hand member m shown in Fig. 10 is indicated as L-shaped and separate from both the member b and t but suitably supported therebetween and the right hand member m is indicated as in the form of a rib integral with the casing b .

In all these constructional forms the pressure of the driving fluid acts externally on the axially divided turbine parts and presses all the axial joints and the flanges and glands together so that they are completely steam-tight and relieves the load on the connecting members. The radial joint between the high pressure casing part and the axial divided lower pressure casing part may be connected in any suitable way for the purpose set forth. A self-tight-jointing turbine casing is thus obtained, in which the undivided cylinder b holding the divided turbine parts together acts as a strengthening cylinder or strengthening shell, while the parts of the casing c lying within the same form the actual jointing cylinder. The separate parts strengthen and stiffen each other relatively and together form an extremely rigid and durable turbine casing.

As the turbine parts lying within the strengthening cylinder are surrounded on all sides and heated by the driving fluid and

are free to expand, when heated, all stresses due to heating are perfectly innocuous and there will therefore be no warping, distortion or any scraping or rubbing of the various turbine parts even at the highest driving fluid temperatures.

What I claim is:—

1. In an elastic fluid turbine, an axially divided casing for the exhaust end thereof having a rotor enclosing casing portion, another casing separate therefrom for the high pressure or admission end surrounding the axially divided higher pressure parts of said rotor enclosing casing portion to form an elastic fluid chamber therearound, and an intake admitting high pressure elastic fluid to said chamber for opposing the internal pressure on the rotor enclosing casing portion.

15 2. In an elastic fluid turbine, an axially divided casing for the exhaust end thereof having a rotor enclosing casing portion, a separate casing for the opposite high pressure end which is capable of withstanding the internal pressure of the turbine and forms an elastic fluid chamber about the rotor enclosing casing portion but on its higher pressure end outside thereof, and an intake admitting to said chamber elastic fluid of sufficient pressure to neutralize to a substantial degree the internal pressure on the rotor enclosing casing portion and thereby tending to substantially counter-balance the strains upon the axial joints of the axially divided parts of the rotor enclosing casing portion.

20 3. In an elastic fluid turbine, an axially divided casing for the exhaust end thereof having a rotor enclosing casing portion, a separate outer casing for the high pressure end which is capable of withstanding the internal pressure of the turbine and surrounds the higher pressure end of the axially divided rotor enclosing casing portion to form an elastic fluid chamber therearound, and an intake admitting to said chamber elastic fluid of a pressure greater than the pressure within the axially divided casing portion whereby the fluid pressure in the chamber assists in maintaining the axial joints 100 tight.

25 4. In an elastic fluid turbine, an axially divided casing for the exhaust end thereof having a rotor enclosing casing portion, a separate undivided outer casing for the opposite high pressure end capable of withstanding the internal pressure of the turbine and surrounding the rotor enclosing casing portion on its higher pressure end to form an elastic fluid chamber therearound, and an intake admitting to said chamber elastic fluid of a pressure greater than the pressure within the rotor enclosing casing portion whereby the pressure of the elastic fluid in 110 said chamber exerts a greater pressure on 120

125 130

the axially divided casing portion in the inward radial direction than in the opposite direction for assisting in maintaining tight axial joints.

5. In an elastic fluid turbine, an axially divided casing for the exhaust end thereof including a cylindrical rotor enclosing casing portion projecting from the exhaust end towards the admission end, a separate casing portion for the higher pressure or admission end capable of withstanding the internal pressure of the turbine and surrounding said cylindrical casing portion of the axially divided casing to form an elastic fluid chamber therearound on its higher pressure end, and a fluid admission connection admitting to said chamber elastic fluid of a pressure sufficient to equalize the pressure of the working fluid within the rotor enclosing casing portion whereby the strain on the axial joints of said axially divided casing is substantially counter-balanced.

6. In an elastic fluid turbine, an axially divided casing on the exhaust end thereof to enclose the rotor, a separate undivided casing for the admission or high pressure end surrounding the rotor enclosing casing portion on its higher pressure end to form an elastic fluid chamber therearound, said separate undivided casing being secured to the rotor enclosing casing portion against strains in the axial direction, and a fluid connection admitting to said chamber elastic fluid of a pressure sufficient to substantially counter-balance the strains upon the axial joints of the axially divided casing.

7. An elastic fluid turbine of the multi-stage type having an axially divided rotor enclosing casing with axial joints maintaining the divided parts of the casing unit in operative position, said casing having a part forming an exhaust chamber and a cylindrical part projecting therefrom towards the admission end and enclosing at least a part of the turbine stages, an undivided casing for the admission side surrounding the cylindrical part of the rotor enclosing casing and forming therewith an elastic fluid chamber therearound separate from the exhaust chamber, said undivided casing being suitably connected to said rotor enclosing casing in abutting relation therewith in a radial plane, and a fluid connection admitting to said chamber elastic fluid of a suitable pressure for the purpose set forth.

8. An elastic fluid turbine having an axially divided rotor enclosing casing on the exhaust end and with axial joints maintaining the divided parts in operative position and an outer casing for the admission end capable of withstanding the internal pressures of the turbine and surrounding the higher pressure end of said axially divided casing and engaging said rotor enclosing casing in a manner to retain the

axially divided parts of the rotor enclosing casing in operative relation.

9. An elastic fluid turbine having an axially divided rotor enclosing casing on the rear end and a separate casing for high pressure fluid on the admission end, surrounding and engaging said rotor enclosing casing on the high pressure end thereof and being suitably connected at its rear end with said axially divided casing so that the pressure on the outer surface of the rotor enclosing casing will substantially counter-balance the internal pressure.

10. In an elastic fluid turbine, an axially divided casing on the exhaust end thereof having a rotor enclosing casing portion, an axially undivided casing portion surrounding said rotor enclosing casing portion on its higher pressure end and forming an elastic fluid chamber therearound, said axially undivided casing portion being secured to said rotor enclosing casing portion against axial strains and externally engaging the same to prevent radial displacement of the axially divided parts, and a fluid admission connection to admit to said chamber elastic fluid of a pressure to equalize the pressure within the rotor enclosing casing portion and assist in maintaining the axial joints of the axially divided parts in tight closing relation.

11. In an elastic fluid turbine, an axially divided casing on the rear end thereof having a rotor enclosing casing portion, a separate casing opposite thereto surrounding said rotor enclosing casing portion on the higher pressure end and forming an elastic fluid chamber therearound, said separate casing being connected to said rotor enclosing casing portion in abutting relation in a radial plane and said casings having distributed reinforcing devices disposed therebetween and within said chamber, and a fluid connection admitting to said chamber elastic fluid of a suitable pressure but higher than the pressure within said rotor enclosing casing portion.

12. An elastic fluid turbine having an axially divided rotor enclosing casing including an exhaust end part and a cylindrical part projecting therefrom towards the higher pressure end and enclosing the rotor and guiding means, divided gland joints for the high pressure end and a reinforcing casing surrounding and engaging the cylindrical higher pressure part of the rotor enclosing casing, said reinforcing casing also enclosing the high pressure end of the turbine and surrounding and engaging the high pressure gland joints to reinforce the same.

13. A multistage elastic fluid turbine having an axially divided rotor enclosing casing with axial joints maintaining the divided parts in operative position and a cas-

- ing capable of withstanding the internal pressure of the turbine which surrounds only the high pressure end of the axially divided casing and engages the same in a 5 manner to retain the axially divided parts of the rotor casing in operative relation.
14. A turbine of the character set forth in claim 8 in which the high pressure admission nozzles are carried by said outer casing.
- 10 15. An elastic fluid turbine having a casing which is divided at right angles to the axis of the turbine and comprises an axially undivided part capable of withstanding high internal pressures, an axially divided 15 rotor enclosing casing part disposed with its higher pressure end within the axially undivided casing part and adapted to be surrounded by the driving fluid, and axially divided internal parts lying within the 20 axially undivided part and being fixed only to the axially divided part of the casing whereby said internal parts are capable of following the expansions due to heat.
16. In an elastic fluid turbine, a casing 25 for the exhaust end thereof having axial joints and a rotor enclosing casing portion on the exhaust end, a separate casing on the admission end surrounding the admission end of the rotor enclosing casing portion to form a chamber for the reception 30 of high pressure fluid, and means for attaching the casing portions together in a manner to cause the high pressure fluid in said chamber to tend to counter-balance the 35 internal pressure on the rotor enclosing casing portion and to keep the axial joints tight.
17. In an elastic fluid turbine, an axially divided casing for the exhaust end thereof 40 having a rotor enclosing casing portion, a separate casing on the admission end to form a chamber around the rotor enclosing casing portion at its higher pressure end for the reception of higher pressure fluid, and 45 means for attaching the two casing portions together in a radial plane to permit the high pressure fluid in the chamber to act inwardly toward the axis to substantially counter-balance the internal pressure on the rotor 50 enclosing casing portion in radial directions.
18. In an elastic fluid turbine, a casing for the exhaust end thereof having axial joints and a rotor enclosing casing portion, a separate casing on the admission end surrounding the admission end of the rotor enclosing 55 casing portion to provide a chamber to receive high pressure fluid, and pressure transmitting means interposed between the admission end and exhaust end casings to reinforce the inner rotor enclosing casing portion by the outer admission end casing.
19. In an elastic fluid turbine, an axially divided casing for the exhaust end thereof 60 having a rotor enclosing casing portion and an outer high pressure casing separate therefrom for the high pressure or admission end surrounding the axially divided higher pressure parts of the rotor enclosing casing portion to form an elastic fluid chamber therearound, and an intake between the first 70 and second stages for admitting high pressure elastic fluid to said chamber for opposing the internal pressure on the rotor enclosing casing portion.
20. In an elastic fluid turbine, an axially divided casing for the exhaust end thereof 75 having a rotor enclosing portion, a separate outer high pressure casing for the high pressure or admission end surrounding the axially divided higher pressure parts connected 80 with the low pressure casing to form an elastic fluid chamber therearound, and an intake between said separate high pressure casing and said rotor enclosing casing portion for admitting high pressure elastic fluid 85 to said chamber for opposing the internal pressure on the rotor enclosing casing portion.
21. In an elastic fluid turbine, an axially divided casing for the exhaust end thereof 90 having a rotor enclosing casing portion, a separate outer casing for the high pressure or admission end surrounding the axially divided higher pressure parts carried by said axially divided casing to form an elastic 95 fluid chamber therearound, and an intake connecting said chamber with the high pressure elastic fluid space at the admission end of said axially divided casing for admitting high pressure elastic fluid to said chamber 100 for opposing the internal pressure on said rotor enclosing casing portion.
22. In an elastic fluid turbine, an axially divided casing for the exhaust end thereof 105 having a rotor enclosing casing portion, a separate outer casing for the high pressure or admission end surrounding the axially divided higher pressure parts of said rotor enclosing casing portion for forming an 110 elastic fluid chamber therearound, and an intake connecting said chamber with the fluid space or clearance between two high pressure elastic fluid to said chamber for opposing the internal pressure on the rotor enclosing 115 casing portion.
23. In an elastic fluid turbine, an axially divided casing for the exhaust end thereof 120 having a rotor enclosing casing portion and a separate casing for the higher pressure or admission end provided with fluid intake or admission means and surrounding the higher pressure end of the rotor enclosing casing portion to oppose the internal pressure thereon.
24. In an elastic fluid turbine, an axially divided casing for the exhaust end thereof 125 having a rotor enclosing casing portion, a separate casing for the higher pressure or admission end provided with fluid intake 130

means surrounding the higher pressure end of the rotor enclosing casing portion and forming therearound a chamber for elastic fluid, and an intake for admitting the elastic fluid to the chamber thereby causing the elastic fluid to oppose the internal pressure on the rotor enclosing casing portion.

In testimony whereof I have signed my name to this specification.

FRANZ LÖSEL.
